Smart Door Lock, by MDHAND on Amazon.com. Dated May 17, 2022. Found online [Aug. 16, 2022]. [Https://www.amazon.com/MDHAND-Keyless-Compatible-Google-Fingerprint/dp/B09Z6R5LRJ.*](https://www.amazon.com/MDHAND-Keyless-Compatible-Google-Fingerprint/dp/B09Z6R5LRJ.*)

Primary Examiner — Marissa J Cash*Assistant Examiner* — Kayla Marie Bennett*(74) Attorney, Agent, or Firm* — Andrew C. Cheng(57) **CLAIM**

I claim the ornamental design for an electronic lock, as shown and described.

DESCRIPTION

FIG. 1 is a front, left and top perspective view of an electronic lock showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the electronic lock in which the design is embodied that form no part of the claimed design.
